UNITED STATES PATENT OFFICE.

EUSTACE CREES AND CHARLES S. COURT, OF PROVIDENCE, RHODE ISLAND,
ASSIGNORS TO THE WATSON AND NEWELL COMPANY, A CORPORATION
OF RHODE ISLAND.

DESIGN FOR A HANDLE FOR SPOONS, FORKS, OR SIMILAR ARTICLES.

SPECIFICATION forming part of Design No. 36,604, dated October 27, 1903.

Application filed August 14, 1903. Serial No. 169,541. Term of patent 7 years.

To all whom it may concern:

Be it known that we, EUSTACE CREES and CHARLES S. COURT, citizens of the United States, residing in the city of Providence, in the county of Providence and State of Rhode Island, have invented a new, original, and ornamental Design for the Handle of a Spoon, Fork, or Similar Article, which is illustrated in the accompanying drawings, forming part of this specification.

Figure 1 represents the obverse of the handle of a spoon, fork, or similar article embody-

ing our design executed in relief; and Fig. 2 shows the reverse of the same.

What we claim is—

The ornamental design for the handle of a spoon, fork or similar article as shown.

In testimony whereof we have signed our names in the presence of two witnesses.

EUSTACE CREES.
CHARLES S. COURT.
